CLAIM

The ornamental design for a handle for manual tools, as shown and described.

DESCRIPTION

FIG. 1 is a top view of a handle for manual tools embodying my new design, the bottom being identical; FIG. 2 is an enlarged side view turned 45° from the position of FIG. 1;

FIG. 3 is a side view thereof;

FIG. 4 is a left end view thereof;

FIG. 5 is a right end view thereof.

The portions of the tool which are shown in broken lines in FIGS. 1-3 are for illustrative purposes only.

The central core which may appear distorted in FIGS. 1 through 3 is of uniform width along its length as shown in FIGS. 4 and 5.

FIG. 1

FIG. 2

FIG. 3

FIG. 4

FIG. 5
